H. J. HOLST

LEDGER

Filed Dec. 24, 1923

INVENTOR

H. J. HOLST
BY Munro & Co.

ATTORNEYS

UNITED STATES PATENT OFFICE.

HANS J. HOLST, OF HILDRETH, NEBRASKA.

LEDGER.

Application filed December 24, 1923. Serial No. 682,451.

My invention relates to improvements in ledgers, and it consists in the combinations, constructions, and arrangements herein described and claimed.

5 An object of my invention is to provide a ledger in which any name in the ledger may be instantly found without the necessity of turning through a number of leaves.

10 A further object of my invention is to provide a device of the type described which employs leaves of novel construction whereby names in the ledger may be readily found.

15 A further object of my invention is to provide a device of the type described in which the leaves are constructed so as to lie in a flat position when the book is opened.

20 Other objects and advantages will appear in the following specification, and the novel features of the invention will be particularly pointed out in the appended claims.

My invention is illustrated in the accompanying drawings forming part of this application, in which—

25 Figure 1 is a plan view of one of the leaves,

Figure 2 is a section along the line 2—2 of Figure 1,

30 Figure 3 is a plan view of two of the leaves shown in open position, and also shows a number of leaves disposed beneath the left-hand leaf,

Figure 4 is a plan view of another form of leaf,

35 Figure 5 is a view showing the position the leaf assumes when the book is opened,

Figure 6 is a modified form of leaf used in the ledger, and

40 Figure 7 is a view showing the sheets in assembled relation.

In carrying out my invention I provide a number of leaves 1, 2 and 2'. The leaves 1 are for the alphabetical list of names, while the leaves 2, 2' are for the separate accounts of people. As clearly shown in Figure 2, the leaf 1 is formed of a relatively stiff paper that is bent back upon itself at 4 so as to provide two layers 5 and 6. A tab 7 is inserted through a slot 8 in the bend 4. It will be noted from Figure 1 that the tab 7 has a reduced portion 9 and an enlarged portion 10. The enlarged por-

tion is disposed between the layers 5 and 6. The shoulders 11 engage with the inner surface of the bend 4 and prevent the tab 7 from being removed. It will also be noted from Figure 2 that the portion 10 is beveled so as to come to a fine point at its inner edge as at 13. A reinforcing strip of cloth 12 or other material encloses the portion 10 and extends beyond it (see Figure 1). The tapering of the portion 10 and the extension of the strip 12 beyond the portion 10 obviates any raised portion which is usually caused on the surface of the sheet by the portion 10. In other words, there is no depression adjacent to the edge of the portion 10.

The leaves 1 are used for alphabetical purposes and in the present instance, I have shown the leaf as having the names starting with C printed thereon. The tab 7 in this instance is also printed with a capital C. The leaf is divided into two columns 14 and 15, the column 14 having surnames thereon which represent a number of accounts of different parties having the same surname, each account being on a separate page, while the column 15 has surnames thereon which represent accounts of different parties, each having a different surname. For example, there would be several "Carlson" and "Cullen" accounts, each one differing from the others by the initials of the first and second names, while there will be just one Chester or Chase account. This is for a purpose hereinafter described. The leaf 1 is also provided with the usual openings 16 through which the posts of the ledger are adapted to extend to secure the leaf in position. A reinforcing strip of cloth 17 or other like material is disposed between the layers 5 and 6 adjacent to the opening 16, whereby the walls of the openings are reinforced.

In Figure 3 I have shown two of the leaves 2, the leaf on the left hand side of the figure showing the arrangement of lines, etc., on one side of the leaf, and the right-hand side of the figure showing the arrangement of lines, etc., on the opposite side of the leaf 2. I will call these sides A and B hereafter. The leaves 2' are printed on both sides in the same manner as the leaves 2, and differ from these leaves

only in the different cut of the free ends of the leaves. The side A of the leaf 2 is clearly shown in Figure 4 and consists of the usual openings 18, which receive the binding posts of the ledger, and in addition slots 19. The slots 19 are disposed in rows and are adjacent to the openings 18. I have found that a leaf of a ledger will bend more easily adjacent to the binding of the ledger when it is provided with slots 19 than when it is not provided with slots. In Figure 5 I have shown the leaf 2 bent adjacent to the slots 19. The outer end of the leaf 2 is cut away at 20 for a purpose now to be described. Figure 3 also shows leaves 21 disposed beneath the top leaf 2 and shows additional leaves 2 disposed beneath the leaves 2'.

The book is made up of a number of sections comprising an index page and a number of leaves disposed directly beneath the index page. The index page is shown in Figure 1 and is in reality the leaf 1, as referred to in the first part of the specification. Figure 7 shows how the index page is provided with a tab 9 that has the letter imprinted thereon which corresponds to the first letter in all of the surnames on the page. Directly beneath the index page or leaf 1, is a leaf 2 similar to the leaf 2'. This leaf is written on the side B so that the matter on the leaf is only readable when the book is opened so as to disclose the leaf on the right-hand side of the book. This leaf is large enough to cover the portions 22 on the leaves 2, but is not large enough to cover the portions 20 and 20' on the leaves 2. Directly below the leaf 2', after the name "Chester, A. W." is a leaf similar to the leaf 2, shown in Figure 3. This leaf has a projection thereon which contains the portions 20 and 22. The projection is disposed at the very top of the page, and therefore the portion 20 refers to the first surname in the left-hand column on the leaf 1, which in the present instance is "Carlson". The leaf 2 is written on the side A so as to dispose the leaf on the left-hand side of the open book when the account of Fred H. Carlson is being checked. The portion 22 disposed adjacent to the blank portion 20 is provided with the letters "F. H." referring to the initials of the man's name. The leaves 2 disposed directly beneath the leaf carrying the portion 20 thereon are provided with projections that are one-half the size of the projection 21. These projections are similar to the portion 22 and bear the initials of the clients in the same manner as the portion 22, heretofore described, bears the initials "F. H". The portions 22 on the succeeding pages are stepped so as to make all of the portions visible as soon as the book has been opened to the leaf bearing the first surname, i. e., the leaf bearing the surname "Carlson" in the present instance.

The next surname on the list 14 is the word "Cullen". The first leaf bearing the surname "Cullen" is provided with a projection 25 which is large enough to be viewed when the leaf bearing the projection 21 is disposed thereover. It will therefore be seen that the leaves which bear the first surname of a series of similar surnames are provided with projections which are stepped in the same manner as the leaves bearing the initials relating to the surnames are stepped. The leaves 1 and 2 are cut so as to permit only the portions 20 and 20' to be visible when the book is closed.

Between the leaf bearing the surname "Cullen" and the leaves bearing the surname "Carlson" disposed directly above the first named leaf is a leaf 2 similar to the leaf containing the surname "Chester". This leaf contains the surname "Chase", which as will be noted, is the second surname appearing on the list 15 on leaf 1. If, therefore, a party wishes to find the account of the client Chase he merely turns to the projection 20' and opens the book, whereupon the page on the right-hand side of the book contains the account of the desired party. The party using the book only has to keep in mind the fact that the surnames in the column or list 14 refer to a number of accounts of different parties having the same surname, while the surnames in column 15 refer to accounts in which each party has a different surname. The finding of the surnames in columns 14 or 15 is identically the same. The second name in column 14 is "Cullen" as heretofore stated, while the second name in column 15 is "Chase". Both of these accounts can be instantly obtained by first noting the position of the surnames in the column. In the present instance they are the second surnames appearing in their respective lists. The second projection 20' on the leaves 2 would instantly open the book and would bring the accounts of Cullen and Chase to view. If Oscar Cullen was not the party desired, the operator could trace down the series of portions 22 and could quickly locate the initials of the Cullen desired, and thus find the desired account.

The book is made up of a series of sections, each section containing the index leaf 1, the leaves 2 bearing the accounts of clients in which one surname refers to more than one client. The leaves 2' refer to accounts in which each surname represents a different client. These sections are bound together in loose leaf form, whereupon the entire book resembles a loose leaf binder in which the tabs 9 containing the letters A to Z respectively, and the portions 20 and 20' are only visible.

As heretofore stated, the surnames in the row 14 of the leaf 1 refer to accounts of a number of persons who have the same

surname. For example, the surname Carlson on the top of the list refers to Fred H. Carlson, on leaf 2 as shown in Figure 3, or John Carlson, on leaf 2' Carlson & Co., on leaf 2', etc. In like manner, the surname Cullen refers to Oscar Cullen as shown in leaf 2 Figure 4, etc. All of the leaves 2 and 2' that have the surname Carlson thereon are to be found beneath the first 10 projection 20 that is disposed directly beneath the leaf 1. In Figure 3 I have shown the leaf that is normally disposed directly beneath the leaf 1. The projection 20 is divided into two portions 21 and 22, the 15 portion 21 being blank while the portion 22 contains the initials of the person's name as for example, in Figure 3, the initials F. H. in the area 22 stand for the name Fred H. Carlson. A person in looking for Fred H. 20 Carlson would merely have to turn to the C tab, and find the position of the name Carlson in the column. In the present instance, the name Carlson is at the top of the list. The person would therefore turn to the 25 top projection 20. The leaves 2' disposed directly beneath the leaf 2 that carries the projection 20 and which bear the surnames Carlson thereon are not provided with projections 20. These leaves, however, are provided with spaces 22 that are similar to the portion 22 that is on the projection 21. After the person has placed his finger upon the desired projection 20, he traces down the initials on the spaces 22 of the leaves 30 25' until he finds the desired initials. The various spaces 22 of the various leaves are so disposed with respect to each other that they may all be read without turning the leaves. For example, the leaf 2' bearing 40 the name Fred H. Carlson is cut at X, while the leaf 2' bearing the name John H. Carlson is cut at Y, etc. In this way, the initials F. H., J. H., etc., may be read without turning the leaves.

45 In like manner, the word Cullen is a surname for a number of people. The first leaf 2 bearing the surname Cullen thereon also has a projection 20' (see Figure 4) that is larger than the projection 20 of the leaf 50 bearing the surname Carlson, whereby the projection 20' may be seen even though the projection 20 is disposed thereabove. In the column shown in Figure 1, the name Cullen is second on the list, and therefore 55 the person looking for the surname Cullen would look for the projection 20' that is disposed directly beneath the projection 20. The leaves 2 and 2' bearing the surname Cullen also have spaces 22' that correspond 60 with the spaces 22, but which are not visible until the book has been opened to the projection 20'. The person then runs down the initials on the spaces 22' until he finds the desired name.

65 The surnames in the column 15 are to only

one person by that name. In Figure 3 I have shown the surname Chester on the side B of the leaf 2. The surnames in the column 14 are to be found on the left-hand side of the book when in an open position, 70 while the surnames in the column 15 are to be found on the right-hand side of the page when the book is opened. The sides B of the leaves 2 and 2' are used for the names found in column 15. 75

From the foregoing description of the various parts of the device, the operation thereof may be readily understood. As heretofore stated, the leaves 1 contain the surnames starting with the same initial. The leaves 2 bear the names of individual persons. The side A of the leaves 2 carries the surnames which are to more than one person, while the side B carries names of which there is only one person. As heretofore 80 stated, an account can be quickly found with this arrangement of leaves. The different cutting of the outer ends of the leaves 2 permits the desired name in the ledger to be quickly found. If desired, a leaf 30 similar to the leaf 2 may be provided which has two lines of perforations 31 and 32 along its outer edge. Transverse lines of perforations 33 divide the rows formed by the lines 31 and 32 into squares. If it is desired to 85 make the leaf of the shape shown in Figure 4, it is merely necessary to tear along the lines a and b. In this way, the person keeping the ledger can add new leaves as desired, and can cut the outer edge of the 90 leaves in the manner he wishes. The device forms a novel way for quickly finding a desired name in the ledger, even though the ledger may have a great many names. The device also obviates the necessity of leafing through a number of pages. 95

I claim:—

1. In a ledger, a leaf having two columns of surnames thereon starting with a common initial, a tab carried by said leaf and having a letter corresponding with the first letter of the surnames, each surname in one of the columns representing a number of accounts of different persons, while each surname in the other column represents only 110 one account of different persons, and a second set of leaves having projections that extend beyond the first named leaf, said projections having data thereon indicating the initials on the leaf carrying the projection, 115 said projections being arranged in consecutive order and referring to the row of names in said first named column.

2. In a ledger, a leaf having two columns of surnames thereon starting with a common initial, a tab carried by said leaf and having a letter corresponding with the first letter of the surnames, each surname in one of the columns representing a number of accounts of different persons, while each sur- 120 125 130

name in the other column represents only one account of different persons, a second set of leaves having projections that extend beyond the first named leaf, said projections having data thereon indicating the initials on the leaf carrying the projection, said projections being arranged in consecutive order and referring to the row of names

in said first named column, and a third set of leaves disposed beneath each one of the second named set of leaves, said third set having projections with data thereon indicating the initials preceding the surname on the sheet carrying the projection. 10

HANS J. HOLST.
